UNITED STATES PATENT OFFICE

FRANS THEODORE CARLSON, OF WAKEFIELD, MASSACHUSETTS

PIANO-ACTION BRACKET

Application filed July 6, 1929. Serial No. 376,412.

My invention relates to improvements in piano action brackets, having particular reference to such as are employed in grand pianos for supporting the action rails upon 5 the key bed.

In the standard grand piano constructions of the prior art, manipulation of the soft pedal to shift the action from three to two strings necessitates the moving of the keys 10 and key frame carrying rigid action brackets which support the rails and action.

This construction and mode of operation is expensive, difficult to maintain in order, entails an unnecessary load for the soft 15 pedal, giving same a tendency toward sluggish action.

It is therefore the primary object of my invention to provide a novel bracket-means to eliminate the necessity for shifting the 20 key frame in the shifting of the action by the soft pedal.

Another object is to furnish a sectional bracket of the class referred to which can 25 be readily installed and used in place of the ordinary bracket without a modification of the usual construction of the action or associated parts.

The invention also resides in certain novel 30 features of construction, combination and arrangement of the various parts and in modes of operation, all of which will be readily understood and appreciated by those skilled in the art upon reference to the accompanying drawing in connection with the 35 detailed description to follow.

It is understood that the drawing illustrates what is now regarded as a preferred 40 embodiment of the invention, although it is to be understood that same is capable of other mechanical expressions within the spirit and scope of the subject matter claimed hereinafter.

Referring to the drawing,

Figure 1 is a side elevational view illustrating the application of my bracket,—the piano action and other well known elements having been deleted for the sake of clarity;

Figure 2 is a front elevational view of the device;

Figure 3 is a view similar to Figure 2, but

showing the position of the parts after the soft pedal has been actuated to shift the action to dispose the hammers for presentation to two strings instead of three as normally.

Throughout the drawing the same reference characters have been used to designate the same parts in all views. Numeral 5 denotes the key frame, 6 the hammer rail, 7 the wippen or support rail and 8 the regulating rail,—all of which are carried by the upper 55 bracket portion 9 which is formed with seats 6^a, 7^a, 8^a, for the respective rails referred to. The parts described are all conventional and well known by those skilled in the art.

My invention resides particularly, as previously stated, in avoiding the necessity for a lateral shift of the key frame 5 in order, through the soft pedal, to shift the action so that the hammers will strike but two wires 60 instead of three, as ordinarily.

The end, aforementioned, is attained by making the action bracket in two parts connected for relative swinging movement.

As will be noted, the upper bracket portion 9 has a depending apertured lug 9^a disposed opposite the depending portion 9^b so as to receive the upstanding portion 10^a of the bracket portion 10 therebetween. Screws 11 extending through portions 9^a, 9^b and into opposite arms of portion 10 serve to pivotally 75 connect the two bracket parts 9, 10.

The lower end of the bracket part 10 is received between the upstanding bearing portions 12^a of cleat members 12 which are secured to the key frame by means of screws 80 or other elements 14, as shown. The upstanding portions 12^a of cleats 12 are transversely bored to provide bearings for the smooth shoulders of screws 13, the ends of which are adapted to be received in threaded 85 bores in the opposed base extensions 10^b of bracket 10.

From the foregoing it will be manifest that the bracket part 9, by reason of pivots 11, 13, 90 may partake of the lateral swinging movement indicated in Figure 3, thus to carry the piano action (not shown) laterally so that the hammers will be disposed to but two strings instead of three.

The device is very simple and can be ap-

plied in lieu of the ordinary bracket with no trouble whatever. The device has the advantage of increased ease in operation, saving of wear and reduces the number of moving parts.

Having thus described my invention, what I claim as new and desire to secure by Letters Patent is:

1. The combination of an action supporting bracket for pianos, a key frame upon which said bracket is mounted, and means in part associated with said frame and in part included in said bracket for permitting lateral shifting of the bracket in an upright plane under the action of the soft pedal of the piano.
2. In a piano construction, an action bracket comprising sections pivotally connected, the axis of said pivot being in parallelism with the key frame, and a pivotal connection between one section of said bracket and said key frame.
3. An action supporting bracket for pianos comprising a pair of sections adapted to be positioned in substantially upstanding continuance of one another, means for pivoting said sections together intermediate their ends, one of said sections being adapted to support the action and having rail seating portions, and the other section having pivot means for attachment to the key frame with the axis of such pivot means being in substantial parallelism with said frame whereby the action carrying section of said bracket may move laterally in a substantial upstanding position under the control of the soft pedal of the piano.
4. An action supporting bracket for pianos comprising a base section having means for pivotal connection to the key frame, an action carrying section pivoted upon said base section and said pivot points being spaced in the direction of the width of said sections.

In testimony whereof I affix my signature.

FRANS THEODORE CARLSON.
